UNITED STATES PATENT OFFICE.

WILLIAM A. JAMESON, OF NIAGARA FALLS, NEW YORK.

DESIGN FOR A BACK OF BRUSHES, MIRRORS, OR SIMILAR ARTICLES.

No. 39,655.

Specification for Design.

Patented Nov. 3, 1908.

Application filed August 4, 1908. Serial No. 447,001. Term of patent 14 years.

To all whom it may concern:

Be it known that I, WILLIAM A. JAMESON, a citizen of the United States, residing at Niagara Falls, in the county of Niagara and State of New York, have invented a new, original, and ornamental Design for Backs of Brushes, Mirrors, or Similar Articles, of which the following is a specification, reference being had to the accompanying drawing, forming a part thereof.

The figure is a plan view of the back of a brush or similar article, showing my design.

I claim:

The ornamental design for the back of a brush, mirror, or similar article, as shown.

WILLIAM A. JAMESON.
